WOMAN'S FOOTWEAR

Esther W. Ellsworth, New York, N. Y.

Application January 16, 1939, Serial No. 251,269

2 Claims. (Cl. 36—7.2)

This invention relates to water-proof foot-wear.

An important object of my invention is to provide a foot covering that is extremely serviceable and of pleasing appearance.

Another object of my invention is to provide a foot covering that will protect the shoe and stocking to a point well above the ankle.

Yet another object of my invention is to provide a foot covering that is sufficiently light in weight to permit the same to be worn during the spring and summer months.

Still another object of my invention is to provide a foot covering that is constructed of a diaphanous material to permit the graceful outline and decorative color of the shoe or slipper to be advantageously displayed.

A further object of my invention is to provide a foot covering that is adapted to be easily and expeditiously applied to and removed from the foot.

Other objects and advantages of my invention will be apparent during the course of the following description.

In the accompanying drawing, forming a part of this specification, and in which like numerals are employed to designate like parts throughout the same,

Figure 1 is a perspective view of my improved foot covering as applied outside of the shoe and stocking and in the open or unbuckled position.

Figure 2 is a side elevation of the same, illustrating the covering in a closed or buckled position, and

Figure 3 is a transverse sectional view taken on the line 3—3 of Figure 2.

In the drawing, wherein for the purpose of illustration, is shown a preferred embodiment of my invention, the numeral 5 designates the vamp or foot-fitting portion adapted to be received over the shoe or slipper 6 with the upper portion 7 thereof of sufficient height to cover the stocking 8 well above the ankle. The sole 9 of the vamp 5 is made of light weight rubber, or the like, and the rear portion 10 thereof is curved upwardly to closely follow the contour of the shank portion of the slipper 6. The upper portion of the vamp 5 is made of any suitable diaphanous material, such as oil silk, formed in two sections and joined centrally by a seam 11 which extends from the toe 12 to the top edge of the upper portion 7. The rearwardly extending portion 13 of the vamp 5 extends in adjacent relation to the sole of the shoe and is

of sufficient length so that opposite portions will meet in overlapping relation at the rear of the slipper.

The portions 13 are slit inwardly to substantially the seam 11, as illustrated at 14 in Figure 1, and straps 15 and 16 are sewn, or otherwise secured therein. The straps 15 and 16 are formed with a straight upper edge 17 and with the lower portions 18 convergent outwardly therefrom toward its middle so that the front of the upper portion 7 will be arcuated to properly conform with the shape of the foot at the instep. The strap 16 is of substantially the same length as the strap 15 and is provided with a vertical slit 19 to receive the strap 15 when the portions 13 are wrapped about the back of the foot, as illustrated in Figure 2. The ends of the straps 15 and 16 are provided with flexible ends 20 of rubber, or the like, having hook and eyelet fasteners 21 and 22 secured theron at their extremities so that when the straps 15 and 16 are wrapped about the ankle, with the strap 15 received within the slot 19, the hook and eyelet 21 and 22 will meet at the forward part of the foot adjacent the instep in a manner whereby the yieldable ends 20 may be sufficiently flexed to bring about the engagement of the fasteners, and to pull the covering neatly about the ankle. The unique construction of the straps will permit the top edge to conform to the comparatively restricted portion of the ankle and the divergent lower portion to properly accommodate the heel and follow the contour of the shoe and ankle. The upper portion 7 terminates at either side thereof in aliform extensions 23 of sufficient length to meet in overlapping engagement at the rear of the leg and comprising upward continuations of the lower portions 13. A strap 24 having a straight upper edge 25 and outwardly convergent lower edge 26 is fastened to the portion 7 substantially equidistant between the top thereof and the lower straps 15 and 16, and with the part of greatest width 27 adapted to be positioned at the back of the leg when the flaps 23 are in overlapping or folded engagement. The ends of the strap 24 are similarly provided with yieldable extensions 28 which are provided with hook and eye fasteners 29 and 30 adapted to substantially meet at the front of the leg and to be brought into engagement by flexing the yieldable portions 28. As illustrated in Figure 2, the aliform formation of the top portion 7 will permit the same to closely follow the contour of the calf of the leg and to present a very neat and pleasing 55

appearance. The edges of the straps 15, 16 and 24, and the exposed edges of the covering 1, are provided with a binding 31 to reinforce and support the same.

5 The transparent light weight upper portion will permit the foot covering to be worn during the warm spring and summer months, and will give ample protection to the foot and stocking during rainy weather to prevent mud and water 10 from being spattered thereon. The diaphaneity of the covering will also give the illusion of smallness to the wearer's foot and eliminate the sensation of bulk commonly associated with the heavier forms of covering. It will also be noted 15 that the lower portion 13 of the covering fits snugly about the heel giving ample protection to this part of the foot. The fastening features are simple and efficient, and the covering as a whole is easily applied to the foot, it being 20 merely necessary to slip the toe of the foot into the vamp 5 and fold the upper portion 7 about the leg with the rear edges thereof in overlapping engagement so that the lower strap 15 may be received within the slot 19 and wrapped 25 about the ankle to permit the hook attached thereto to engage with the eyelet secured to the end of the strap 16. The upper strap 24 is then similarly wrapped about the leg above the ankle, and the hook and eyelet 28 and 30 secured to respective ends thereof brought into 30 engagement at the front of the leg. The flexible nature of the ends will cause the covering to closely conform with the shape of the leg and to permit the wearer to enjoy a free walking 35 movement.

It is to be understood that the form of my invention, herewith shown and described, is to be taken as a preferred example of the same, and that various changes in the size and shape 40 of the parts may be resorted to without departing from the spirit of my invention or the scope of the appended claims.

Having thus described my invention, I claim:

1. A foot covering comprising a sole extending from the toe to the heel of the shoe to be covered; an upper attached to the sole, said upper having portions extending rearwardly thereof a sufficient length to meet in overlapping engagement at the rear of the said shoe, the lower edge of said portions closely following the union of the upper with the sole of the shoe, the top portion of the said upper extending to a point above the ankle of the wearer 45

and terminating at either side thereof in aliform configuration, said upper having transverse slits extending inwardly from either side thereof at approximately the ankle of the wearer and opening through the rearward edge thereof above the 5 said lower edge; straps fitted into the said slits and formed with a straight upper edge and with a V-shaped lower portion, said straps being adapted to be wrapped around the ankle of the wearer and being adapted to meet at substantially the front of the ankle; elastic members secured to the outer ends of the said straps to cause the upper to fit closely and correspond substantially to the contour of the ankle; and fasteners attached to the said elastic members. 10 15

2. A foot covering comprising a sole extending from the toe to the heel of the shoe to be covered; an upper attached to the sole, said upper having portions extending rearwardly thereof and being of sufficient length to meet in overlapping engagement at the rear of the said shoe the lower edge of which closely follows the union of the upper with the sole of the shoe, the top portion of the said upper extending to a point above the ankle of the wearer and terminating at either side thereof in aliform configuration, said upper having transverse slits extending inwardly from either side thereof at approximately the ankle of the wearer and opening through the rearward edge thereof above the 20 25 30 said lower edge; straps fitted into the said slits and formed with straight upper edges and with V-shaped lower portions having the apexes thereof co-incident with the rear of the said side pieces, said straps being adapted to be wrapped around the ankle of the wearer and being adapted to meet at substantially the front of the ankle; elastic members secured to the outer ends of the said straps to cause the upper to fit closely and correspond substantially to the contour of the ankle; fasteners attached to the said elastic members; a strap secured to one side of the upper having a straight upper edge and a V-shaped lower portion, the apex of which is co-incident with the rear edge of the 45 50 said upper, said strap being adapted to be wrapped around the leg of the wearer and to cause the upper to fit closely and correspond substantially to the contour of the leg; elastic members attached to the ends of the said strap; and fasteners attached to the said elastic pieces.

ESTHER W. ELLSWORTH.
